corporation of New York

Application July 16, 1938, Serial No. 219,607
In Germany July 19, 1937

4 Claims. (Cl. 178—69.5)

In television transmissions in which the scanning of the picture takes place by means of an iconoscope or the like there result at the receiver distortions of the picture which, in the case 5 of picture of high definition, may assume unacceptable proportions. These distortions are based on the chronological delay of the synchronization impulses in relation to the image signals which result by way of the modulating 10 stage of the transmitter and the demodulating stage of the receiver.

The Figs. 1-3 are intended to explain the operation of an arrangement of this kind. There is:

- 15 1 the iconoscope of the transmitter,
- 2x the synchronizing impulse generator for the line deflection on the transmitter,
- 2y the synchronizing impulse generator for the frame deflection,
- 20 3x the relaxation oscillation generator for the line deflection,
- 3y the relaxation oscillation generator for the frame deflection,
- 25 4 the amplifier of the transmitter,
- 5 the modulator of the transmitter,
- 6 the transmitter,
- 7 the receiver,
- 8 the demodulator,
- 30 9 the amplifier,
- 10 the separator for separating the synchronizing impulses at the receiver,
- 11x the relaxation oscillation generator for the line deflection at the receiver,
- 35 11y the relaxation oscillation generator for the frame deflection at the receiver,
- 12 the cathode ray tube at the receiver,

In Fig. 1 the iconoscope 1 possesses a pair of deflecting plates each for the horizontal and the 40 vertical deflection. The deflecting potentials are generated in the relaxation oscillation generators 3x and 3y, which are controlled by the impulse generators 2x and 2y. In the amplifier 4 there are amplified the synchronization impulses of the generators 2x and 2y and the image 45 transmission, and in the modulator 5 following thereon the carrier wave of the transmitter is modulated by this image potential mixture and passed to the transmitter 6. At the receiver the 50 synchronization impulses are filtered out by a separating device and employed for controlling the relaxation generators 11x and 11y for the deflecting potential of the Braun tube.

The instants of the image signals caused by 55 the scanning in an iconoscope of the transmitter

are dependent on the deflecting oscillations controlled by the synchronizing impulses. The instants of the image signals reproducing the image at the screen of the cathode ray tube of the receiver are dependent on the image signals given 5 from the transmitter. The deflecting oscillations for deflecting the cathode ray at the receiver is also controlled by the impulse given from the impulse generator of the transmitter. These synchronizing signals are longer delayed 10 on the way between the impulse generator of the transmitter and the deflecting oscillator of the receiver, than the image signals on the way between the iconoscope of the transmitter and the cathode ray tube of the receiver, since the synchronizing impulses pass more elements than the image signals, and since the passed elements delay the synchronizing impulses longer than the image signals. Therefore, at the receiver the positions of the image signals on the reproduced image are displaced in view of the positions of the image signals on the transmitted picture.

The subject matter of the invention is an arrangement for eliminating the distortions of the 25 picture at the receiver. This takes place by the fact that the impulses which for controlling the relaxation generators 3x, 3y for the iconoscope 1 at the transmitter end experience the same delay as the impulses for controlling the relaxation generators 11x, 11y for the cathode ray tube 30 12 at the receiver.

The arrangement according to the invention is explained by Fig. 2. The synchronization impulses of the generators 2x and 2y are conducted 35 only in the known fashion with the image signals to the transmitter for controlling the receiver. The connection between the impulse generators 2x, 2y and the relaxation oscillation generators 3x, 3y as shown in Fig. 1 is omitted. 40 At the aerial coil of the transmitter 6 there is provided a receiving device 7, which receives the television transmissions. The synchronization impulses are filtered out by a separating device 10 in the known manner from the mixture received and employed for controlling the relaxation generators 3x, 3y for the iconoscope 12. The delays in the synchronization impulses between the impulse generator of the transmitter and the relaxation generator of the receiver accordingly 45 exactly correspond to the delays in the impulses from the impulse generator to the relaxation generator for the iconoscope. In this way it is accomplished that differences in time between the deflecting potentials and the 50 55

image potentials at the cathode ray tube of the receiver are eliminated. The arrangement can also be employed if records are to be made by an iconoscope at a comparatively large distance away from the transmitter. In this case the control of the relaxation potential generators of the iconoscope also takes place by the impulse generators of the transmitter by way of a special receiving device.

10 Fig. 3 shows a possibility of use of this kind. A television transmission is to be recorded by means of the iconoscope at a comparatively long distance away from the transmitter, for example on a playing field. The impulse generators 2x and 2y are located at the television transmitter. The synchronization impulses are transmitted in wireless fashion to the portable recording apparatus, where they are employed for controlling the relaxation oscillation generators 15 3x, 3y located there. In this way it is possible to make the portable recording apparatus more simple in design and to ensure the synchronization of the receiver by the transmitter. The record to be transmitted can be conveyed from the recording apparatus to the transmitter by a wire connection or special cable. It is also possible, and particularly convenient, to perform the transmission in wireless fashion by the use of an auxiliary transmitter. In this connection there 20 can be employed for the auxiliary transmitter a desired frequency or the same frequency as that of the main transmitter or half the frequency or another sub-harmonic frequency of the main transmitter. If there is employed for the auxiliary transmitter the same frequency as for the main transmitter, the main transmitter acts as 25 amplifier. In this case modulating stages and demodulating stages in the main transmitter can be dispensed with. When using one-half of the 30 frequency or any other sub-harmonic frequency of the main transmitter a frequency doubling or multiplication requires to be performed at the main transmitter. This method possesses in face of the method previously mentioned the advantage that reactionary effects of the main transmitter on the auxiliary transmitter are avoided. In Fig. 3 there is shown a wire connection for transmitting the contents of the picture to the transmitter.

I claim:

1. In a television transmitter a cathode ray tube for scanning the picture, deflecting oscillators for deflecting the cathode ray of said cathode ray tube in the vertical direction and in the horizontal direction, generators generating impulses controlling said deflecting oscillators and synchronizing the deflecting oscillators of the receiver, delaying means consisting of a special device receiving the synchronizing impulses transmitted by the transmitter and being coupled via a demodulator, an amplifier amplifying said impulses and a separating device separating the line and frame synchronizing impulses from the image signals and each from one another to the deflecting oscillators of said scanning cathode ray tube, said special receiving device and said iconoscope being placed in a comparatively long distance from the other parts of the transmitter, only the scanning electrode of the iconoscope being connected by cable to the modulator of the transmitter, said special receiving and said iconoscope being mounted in a transportable television scanning apparatus.

deflecting oscillators of said scanning cathode ray-tube.

2. In a television transmitter a cathode ray tube for scanning the picture, deflecting oscillators for deflecting the cathode ray of said cathode ray tube in the vertical direction and in the horizontal direction, generators generating impulses controlling said deflecting oscillators and synchronizing the deflecting oscillators of the receiver, delaying means consisting of a special device receiving the synchronizing impulses transmitted by the transmitter and being coupled via a demodulator, an amplifier amplifying said impulses and a separating device separating the line and frame synchronizing impulses from the image signals and each from one another to the deflecting oscillators of said scanning cathode ray tube, said special receiving device and said scanning cathode ray tube being placed in a comparatively long distance from the other parts of the transmitter.

3. In a television transmitter an iconoscope for scanning the picture, deflecting oscillators for deflecting the cathode ray of said cathode ray tube in the vertical direction and in the horizontal direction, generators generating impulses controlling said deflecting oscillators and synchronizing the deflecting oscillators of the receiver, delaying means consisting of a special device receiving the synchronizing impulses transmitted by the transmitter and being coupled via a demodulator, an amplifier amplifying said impulses and a separating device separating the line and frame synchronizing impulses from the image signals and each from one another to the deflecting oscillators of said scanning cathode ray tube, said special receiving device and said iconoscope being placed in a comparatively long distance from the other parts of the transmitter, only the scanning electrode of the iconoscope being connected by cable to the modulator of the transmitter.

4. In a television transmitter an iconoscope for scanning the picture, deflecting oscillators for deflecting the cathode ray of said cathode ray tube in the vertical direction and in the horizontal direction, generators generating impulses controlling said deflecting oscillators and synchronizing the deflecting oscillators of the receiver, delaying means consisting of a special device receiving the synchronizing impulses transmitted by the transmitter and being coupled via a demodulator, an amplifier amplifying said impulses and a separating device separating the line and frame synchronizing impulses from the image signals and each from one another to the deflecting oscillators of said scanning cathode ray tube, said special receiving device and said iconoscope being placed in a comparatively long distance from the other parts of the transmitter, only the scanning electrode of the iconoscope being connected by cable to the modulator of the transmitter, said special receiving and said iconoscope being mounted in a transportable television scanning apparatus.
